ABSTRACT

Apparatus for monitoring the motion of a filling thread in weaving machines with shuttles for stopping the weaving machine when there is a break in the thread. The apparatus comprises a signal transmitter in the shuttle having an active electronic component which is influenced by the filling thread passing from the shuttle, a signal receiver positioned outside of said shuttle responding to said signal transmitter for controlling a device for stopping the weaving machine, and means externally of the shuttle for electromagnetically generating electrical energy and supplying it to the electronic component carried by the shuttle.

APPARATUS FOR MONITORING SHUTTLE FILLING THREAD

This is a continuation, of application Ser. No. 259,348, filed June 2, 1972 now abandoned, which in turn is a continuation of application Ser. No. 869,643, filed Oct. 27, 1969, now abandoned.

It is to be understood that the above Abstract of Disclosure is submitted in compliance with the requirements of the United States Patent Office, Rule 72 (b), Rules of Practice in Patent Cases, and is not to be used in the construction of, or as limiting, the scope of the invention as hereinafter defined in the Appended claims.

BACKGROUND OF THE INVENTION

1. Field of the Invention

The present invention relates to a filling thread monitoring apparatus for use with weaving machines having shuttles. More particularly, the present invention relates to apparatus for supplying electrical energy to the active electronic component in the signal transmitter of a filling thread monitoring apparatus independent of a source of such energy carried by the shuttle.

2. Description of the Prior Art

In a weaving loom having a shuttle it is necessary to check whether the filling thread is being drawn from the filling bobbin, i.e., whether the thread is moving in the space between the filling bobbin and the point where it leaves the shuttle. For this purpose, the shuttle may carry a signal generator which transmits a signal, generated by the motion of the filling thread when it runs off the filling bobbin, to a signal receiver. If this signal does not occur during the sensing interval, the loom is stopped by the signal receiver.

In a filling thread monitor of the type described in the preceding paragraph, the signal generator comprises a miniature switch and a high frequency transmitter actuated by said switch. Electrical energy must be supplied to the transmitter and also any amplifier circuit associated therewith, at least during the desired operating period. To accomplish this, the shuttle may contain a source of current such as a small battery or other energy storage means. This solution has substantial disadvantages, primarily as a result of the small capacity and therefore the short life of the batteries or storage cells which can be considered for this application. Frequent changing and the necessary frequent periodic inspection of the condition of the built in current source are impossible when such a device is actually used in a weaving mill unless the machinery is first shut down. In addition, to switch the current source on and off every time it is inspected would also require sophisticated equipment.

SUMMARY OF THE INVENTION

It is an object of the present invention to provide a filling thread monitoring apparatus having a signal transmitter in which the supply of energy for the transmitter is independent of a source of current carried along.

It is another object of the present invention to provide a filling thread monitoring apparatus in which the independent supply of energy is only furnished during the sensing interval of the monitoring apparatus.

It is a further object of the present invention to provide a filling thread monitoring apparatus with a supply

of energy for the signal transmitter which does not require frequent periodic inspection to determine its usefulness.

In accordance with the objects of the invention there is provided a filling thread monitoring apparatus for a thread carrying shuttle of a weaving machine in which the supply of energy is independent of a current source carried along with the shuttle. The filling thread monitoring apparatus of the invention has a signal transmitter positioned in the shuttle with an active electronic component that is influenced by the filling thread. Concurrently the active electronic component is supplied with electrical energy by means of a device along the trajectory of the shuttle. For this purpose, the signal transmitter comprises preferably an induction coil which during the travel of the shuttle intersects the field of a permanent magnet which is placed alongside the trajectory of the shuttle.

Also in accordance with the present invention there is provided a signal receiver positioned outside of the shuttle for controlling a device which halts the weaving machine in response to a predetermined signal from the transmitter.

By the practice of this invention, therefore, the proper sensing of the thread and operation of the weaving machine are accomplished without the drawbacks of the heretofore available filling thread monitor.

Additional objects and advantages will be set forth in part hereinafter and will be obvious herefrom or may be learned by practice with the invention, the same being realized and attained by means of the steps, combinations and improvements pointed out in the appended claims.

Furthermore, the accompanying drawings referred to herein and constituting a part hereof illustrate the invention and together with the description serve to explain the principles thereof.

BRIEF DESCRIPTION OF THE DRAWING

The invention will be described and understood more readily when considered with the attached drawing in which:

FIG. 1 shows a part of a shuttle from above, when it is leaving the shed, with a built in signal transmitter, together with elements comprising a portion of the signal receiver, shown in cross-section;

FIG. 2 is a front cross-sectional view, partially broken-away, of the elements illustrated in FIG. 1;

FIG. 3 shows a schematic circuit diagram of a filling thread monitoring apparatus according to the invention.

DESCRIPTION OF THE PREFERRED EMBODIMENT

The sensing of the filling thread occurs preferably toward the end of the period when the filling is placed in the fabric and consists in checking whether the filling thread is still drawn from the filling bobbin. For this purpose the shuttle carries a signal transmitter which transmits, within a definite sensing interval, a signal, which is generated by the motion of the filling thread when it runs off the filling bobbin, to a signal receiver. The motion of the filling thread is an unequivocal criterion for the intact condition of said thread when it is placed in the fabric. If the above mentioned signal does not occur during the sensing interval, the loom is stopped by the signal receiver.

This concept of filling thread sensing makes it possible to supply electrical energy to a signal transmitter comprising an active electronic component, for instance an amplifying transistor or oscillator circuit, not continuously but only during the sensing interval.

Now referring to FIGS. 1 and 2, shuttle 1 is just leaving the shed, which is formed by the warp threads (not shown), moving from left to right with its rear part still above the batten 2 and in front of the reed 3. The thread 5 pulled from the filling bobbin 4 runs through the guide 6 and over a thread sensing means 10, 11 arranged therein, leaving the shuttle through bushing 7. In the guide 6 the filling thread is deflected between the two guide bushings 8 and 9 on a fixed small friction plate 10, which consists for example of a ceramic material based on oxides. Since the friction plate is fixed, the thread travels a path through the guides 8, 9 and over the plate 10, which is essentially independent of the degree of thread tension. Beneath friction plate 10 is a small plate 11 made from an electrically conductive material which is electrically connected to a circuit consisting of the components mounted on plate 12. The space 13 in which the electrical components are located, is filled with an insulating potting compound.

The signal transmitter comprises an induction coil 15, which is provided with an electrically conductive shield 14 inserted in the side wall of shuttle 1 facing reed 3, which is part of the electric circuit of the signal transmitter described hereinafter.

A rectangular induction coil 17 is attached to the batten 2 by means of the not completely shown fastening means 16, coil 17 is the actual receiving means of the signal receiver. Coil 17 is connected by means of terminals 18 and 19 with the output section of the signal receiver which will also be described hereinafter. Terminal 19 carries the potential of electric shield 20 surrounding coil 17. A permanent magnet 21 is placed inside coil 17 such that pole 22 of magnet 21 is at a greater distance from reed 3 and at a smaller distance from the trajectory of shuttle 1 than pole 23 which is closer to reed 3, thus providing a traverse magnetic field that varies in strength relative to the direction of shuttle motion. The permanent magnet 21 is potted inside coil 17.

Now referring to FIG. 3, the circuit contains first the signal transmitter, located in shuttle 1, consisting the components 11, 24, 25, 26, 27 and 15. In this circuit, the above mentioned conductive plate 11 is connected through a capacitor 24, with a capacity for example of several μ F, with the control electrode (gate) of a field effect transistor 25. The input circuit of transistor 25 contains a resistor 26 of approximately 10 megohms, while the drain source circuit contains an induction coil 15 and a diode 27 which are connected in parallel.

The signal receiver comprises the induction coil 17 and a circuit represented by the elements 28 to 36 whose purpose and function will be described in more detail below. The elements 37 to 40 are for the purpose of stopping the weaving machine and will also be described in more detail below.

In operation, the intact filling thread 5 runs from the bobbin 4 over the friction plate 10 in the guiding section 6 of shuttle 1, short variations in the electric potential are generated triboelectrically, i.e., by frictional generation of electricity in the small conductive plate 11 which arrive, through capacitor 24, at the control electrode of the field effect transistor 25. The electrical

energy supplied to transistor 25, which acts as an amplifier, is obtained from the kinetic energy of shuttle 1 when it passes permanent magnet 21. If the coil 15 moves, in particular when the shuttle leaves the shed, past magnet 21, an electromotive force is induced whose shape is, due to the spatial arrangement of the magnet shown in FIG. 1, that of an extended flat pulse, followed by a short, steep pulse of the opposite polarity. The flat pulse, which is generated in the coil by the steady increase of the magnetic field from the time it enters the field to the time it leaves the area of pole 22, supplies the voltage required for operation of transistor 25, while particularly high voltage peaks of the opposite polarity are by-passed through the diode 27 in order to protect transistor 25.

The time when the voltage pulse occurs determines the time when the filling thread 5 is checked. If the filling thread is intact at that time, the variations in potential on the control electrode of transistor 25, which were mentioned above, will cause a modulation of the current flowing through coil 15. Due to the inductive coupling of coils 15 and 17 during the passage of shuttle 1, corresponding voltage variations will be generated at input terminals 18, 19 of the signal receiver, which contain frequency components in the range between approximately 5 kilocycles and 50 kilocycles.

On this signal voltage will be superimposed at terminals 18, 19 the voltage pulses which are generated by the inductive transmission to coil 17 of the transistor operating voltage induced in coil 15. In the latter voltage pulses the low-frequency components with frequencies up to approximately 1 kilocycle predominate.

The total of the voltage variations generated at terminals 18, 19 is first amplified in amplifier 28 and then fed to filters 29 and 34. Filter 29 is a high-pass filter and its purpose is to separate the part of the signal which signifies the running of thread 5 from the total voltage variations, for example the frequencies above 5 kilocycles, and to feed these frequencies to amplifier 30. Filter 34 is designed as a low-pass filter, for instance with a cut-off frequency of 500 cycles to 1 kilocycle and is used for separating and passing the low-frequency components which characterize the pulses of the supply voltage.

Filter 34 is followed by a pulse-shaper 35 which is triggered by the positive voltage pulse induced by the front of the supply voltage pulse and which generates a square pulse of predetermined length which is a little shorter than the length of the supply voltage pulse. This square pulse is fed into coincidence network 36 at whose second input terminal a signal pulse arrives simultaneously if the thread is running off bobbin 4 properly. The signal pulse is generated in the following manner by the circuit shown in FIG. 3: The high-frequency voltage variations at the output terminal of filter 29 are greatly amplified (block 30) and compressed (block 31). The signal which emerges has very steep fronts. By subsequent full-wave rectification (block 32) and smoothing in a low-pass filter (block 33) a pulse of practically constant height is obtained whose length corresponds to the length of the high-frequency variations of the signal voltage.

The simultaneous occurrence of the signal pulse and of the corresponding gate pulse generates at the output terminal of coincidence circuit 36. This pulse, which confirms that the filling thread was not broken at the

instant of sensing, actuates elements 37 to 40 which can trigger the stopping of the loom.

For this purpose the output pulse of coincidence circuit 36 is fed into one of the input terminals of the anti-coincidence network 37 whose second input terminal is connected to a pulse generator 38. Logic network 37 causes a conjunctive combination of the input signals, but with a negation of the first input. Logic network 37 delivers an output pulse only if a pulse arrives at the second input terminal and there is no signal arriving at the first input terminal at the same time.

Pulse generator 38 is driven by the drive mechanism of the weaving machine, for example by means of a control cam attached to the crankshaft which carries a small permanent magnet on its periphery acting on a stationary induction coil. The phase angle of the triggering pulse generated by pulse generator 38 is chosen in such a manner in relation to the operating cycle of the weaving machine, that this trigger pulse arrives at anti-coincidence network 37 simultaneously with the signal pulse generated by coincidence network 36 which, when the filling thread 5 runs off normally, arrives at the instant when shuttle 1 leaves the shed. Anti-coincidence network 37 then delivers no output pulse. If the filling thread is broken, however, the signal pulse at coincidence network 36 is missing when the triggering pulse arrives from pulse generator 38 and the anti-coincidence network 37 then generates an output pulse. This pulse causes stopping of the loom through a relay device 39 and the actual tripping circuit 40 which contains, for instance, a tripping solenoid.

It is important that in the circuit shown in the drawing, the shutting off of the loom always takes place when the signal, which indicates proper running-off of the filling thread, is missing, and also if the signal transmitter or receiver are not functioning properly. By coupling the triggering pulse with the drive mechanism of the loom we are also assured that the sensing interval is defined with relation to the trajectory of the shuttle. The filling thread is to be sensed at the instant, and only at the instant, when the shuttle emerges from the shed. The passage of the shuttle past the signal receiver when it enters the shed has no effect on the tripping circuit, as no triggering pulse is generated at that instant. In order to obtain complete monitoring of the filling thread, an analogous device consisting of receiver coil and permanent magnet, exactly as shown for one side of the batten, is required for the other side of the batten. The second receiving coil is also connected to terminals 18, 19 or, preferably, to an amplifier, similar to amplifier 28, whose output terminals are connected in parallel with those of amplifier 28.

It should also be mentioned that FIG. 3 shows only the components which are important for explaining the functioning of the circuit. In order to simplify the drawing, the intermediate amplification and delay stages, which are obvious to the expert, have been omitted. Such intermediate stages are, for example, provided to assure that the input pulses of the coincidence and anti-coincidence networks, 36 and 37, normally coincide, even if the dispersions in time and space due to the functioning of the weaving machine are taken into account.

The transmission of the energy required for the operation of the signal transmitter in the flying shuttle can, in principle, also take place by means of electrical or electromagnetic fields. Amongst the latter fields, the

greatest practical importance can probably be assigned to a beam of light rays cooperating with a photoelectric converter in the shuttle.

Preferably a magnetic field is used, however, for the transmission of energy, either in the form of a static field, as in the above described case of a permanent magnet, or as an alternating field, such as the field created by an induction coil. The frequency of the alternating field is then chosen in such a way that it can be clearly separated in the receiver from the frequency band of the signal voltage variations.

Another embodiment is characterized in that the transmissions of energy and signal are separated in time. In this design, the electro-motive force which is induced in a coil in the shuttle causes, for instance, the charging of a capacitor which serves as an energy-storage device up to the instant when the signal is transmitted. Such storage permits spatial separation of the elements used for the transmission of energy and of those used for the transmission of the signal. The shuttle may, for example, carry one coil each for the reception of energy and for the transmission of signals, respectively, in its two ends, or in one of its ends and in one side wall. In the output circuit of the transistor the signal transmitting coil is then connected in series with a storage capacitor, and parallel to said capacitor is circuit containing the energy receiving coil and a rectifier, connected in series.

The advantages of the energy transmission to the signal transmitter in the shuttle, in accordance with the invention, have a decisive effect, most importantly in the practical operation of such a filling thread sensor. The signal transmitter requires neither maintenance nor inspection; its ability to operate correctly does not depend on any short lived component, but it is always ready to operate. The filling thread monitor described above, represents, in addition, a substantial simplification of the equipment, as the transmission of energy and the transmission of signals can be effected by a combined device on the weaving machine.

What is claimed is:

1. In apparatus for monitoring the motion of a filling thread in a shuttle of a weaving machine, the apparatus having signal transmitting means carried by the shuttle for developing a signal representing the condition of the thread, and signal responsive means physically independent of the shuttle and responsive to the signal transmitter, the combination of:

triboelectric sensing means mounted in the shuttle immovably for developing electrical potential variations comprising a sensing signal representing movement of the thread through the shuttle; the transmitting means including electronic means carried by the shuttle for amplifying the sensing signal to a level suitable for transmission; and electrical energy supplying means including a first device positioned adjacent the shuttle trajectory and a second device carried by the shuttle, the first and second devices being electrically cooperative to generate and supply electrical energy to the electronic amplifying means upon passage of the shuttle by the first device.

2. The apparatus of claim 1, wherein the energy supplying means includes:

a magnetic device for developing a magnetic field traversing the trajectory of the shuttle; and

means carried by the shuttle for electromagnetically interacting with the magnetic field to develop an electrical potential signal supplied to the amplifying means.

3. The apparatus of claim 2, wherein: the interactive magnetic field varies in strength relative to the direction of the shuttle trajectory.

4. The apparatus of claim 3, wherein: the weaving machine includes a batten; and the magnetic field means comprises a permanent magnet attached to the batten disposed to have a magnetic axis angularly related to the trajectory.

5. The apparatus of claim 1, wherein: the electronic amplifying means comprises a semiconductor amplifier; and

the energy supplying means is effective to develop an electrical pulse of sufficient magnitude and duration to cause the semiconductor device to conduct and thereby amplify the generated electrical signal supplied thereto during the occurrence of the 20 pulse.

6. The apparatus of claim 1, wherein: the sensing means comprises a friction element and an electrically conducting element associated therewith for developing the generated electrical 25 signal.

7. The apparatus of claim 1, further comprising: means carried by the shuttle for temporarily receiving and storing electrical energy to be supplied to the amplifying means by the energy supplying 30 means.

8. The apparatus of claim 6, wherein: the friction element is made of oxide ceramic material.

9. The apparatus of claim 1, further comprising: means fixedly mounted in the shuttle for guiding the moving filling thread in a path adjacent the sensing means, said path being independent of the tension of the thread.

10. In apparatus for monitoring a filling thread carried by the shuttle of a weaving machine and including means for producing a signal representing the condition of the thread, a signal transmitter in the shuttle, and a signal receiver positioned to receive the signal from the transmitter:

15 sensing means for generating an electrical signal having potential variations related to movement of the filling thread through the shuttle and substantially independent of the degree of tension of the thread;

active electronic means carried by the shuttle and electrically coupled to the transmitter for amplifying the electrical signal to be transmitted; and means including an element carried by the shuttle and a device positioned adjacent the trajectory of the shuttle, such element and device being electrically cooperative to supply electrical energy to the signal amplifying means upon movement of the shuttle therest.
